(57) CLAIM

The ornamental design for a comb handle, as shown and described.

DESCRIPTION

FIG. 1. is a perspective view of a comb handle showing my new design thereof;

FIG. 2. is a front view thereof;

FIG. 3. is a rear view thereof;

FIG. 4. is a left side view thereof;

FIG. 5. is a right side view thereof;

FIG. 6. is a top plan view thereof; and,

FIG. 7. is a bottom plan view thereof.

The broken lines illustrate portions of the comb handle that form no part of the claimed design.
